UNITED STATES PATENT OFFICE.

JNO. PLANT AND CHS. G. BALL, OF WASHINGTON, DISTRICT OF COLUMBIA.

COOKING-RANGE.

Specification of Letters Patent No. 14,591, dated April 8, 1856.

To all whom it may concern:

Be it known that we, JOHN PLANT and CHAS. G. BALL, of the city of Washington and District of Columbia, have invented 5 certain new and useful Improvements in Cooking-Ranges; and we do hereby declare that the following is a full, clear, and exact description of the same, reference being had to the accompanying drawing, making 10 a part of this specification.

The nature of our improvement consists in arranging the several fire chambers, so that by bridging the ash-pit, we are enabled to place the descending flues in such a position as to cause the heat and products of 15 combustion to pass under the front of ovens placed between each pair of fire chambers; while at the same time we obtain the full benefit of the fire on the sides of the ovens 20 by the contact of the sides of the fire chambers therewith, and use the heat in its passage to the smoke stack flues for heating the rear of the oven by appropriate flues, thereby obtaining the diffusion of heat more 25 equally over the whole range and area of each oven than heretofore has been obtained.

We also combine with this improvement 30 of the flues, that of the ascending smoke stack flues by having so arranged them by inclination, that the draft shall be equalized when all the fire chambers are in use and open; or when a portion of those chambers are in use.

35 The major part of the range is of brick work laid in suitable cement; the front and top plate being of iron as well as the ovens and fire grates. To make the range complete we use water backs to our fire chambers so as to insure an abundance of hot water.

In the accompanying drawings A A A A are the fire chambers, the sides and front 45 b b b, formed of clay tile; the remaining side c a hollow iron water back; a tilting grate or set of bars (a) completes the fire chamber.

B B B represent ovens formed either of sheet or cast iron placed between each pair 50 of fire chambers, the front of the oven extending to the front plate (d) of the range; it is most simply closed by sliding doors (e, e, e).

D D D are bridges formed of brick or

metal, placed over the ash pit E, and with 55 the sides of the ovens forming the diving flues F, F, F F.

G G G are flues from under the ovens, leading to the smoke stack flues H H.

At the rear of the sides (b, b) Figs. 2 and 60 4 of the fire chamber a portion of the top edge is cut out, thus forming an exit flue (x) from the fire chamber; I, I are connecting leads or flues uniting the flues H H, 65 conducting the smoke (if any) to the center flue K which may be connected with the chimney.

The ash pit doors are furnished with suitable registers for the admission of air under the grates.

To understand the operation of this improved range or ovens, it will be noticed, 70 that while the whole heat from the fire chamber on the right or left of the range is passed by its diving flue, that only the one half of the heat from the adjoining fire chamber, say No. 2, passes by the diving flue on the right side of the bridge, while the other portion of heat from No. 2 passes to the next oven by its diving flue, and 75 so in succession to each oven, all receiving a portion of the heat from two fires. By thus dividing the heat, it is more regularly diffused throughout the whole range of ovens and a degree of heat obtained by 80 passing it under the ovens, by which their floors are heated and thus the baking property is secured in them.

In starting the fire in this range, the covers of the fire chambers may be placed on 90 the openings of the top plate, but after the draft is established the removal of the cover admits the excess of atmospheric air, which commingling with the products of combustion insures the more perfect combustion 95 thereof, and as this takes place in the diving flues and under the ovens, a material saving of fuel results, while all escape of gases is prevented. As the top plate over the ovens is kept at a sufficient heat for the purposes 100 of cooking; by placing stew pans and boilers thereon a vast increase of cooking space is secured without interfering with that over the fire chambers.

Figure 1, is a view of the range with the 105 smoke flues or pipes in place; Fig. 2 a top view with the top plate removed; Fig. 3 a longitudinal section (enlarged); Fig. 4 a

transverse section under the ovens; Fig. 5 a transverse section through the fire chamber.

We do not claim the alternate arrangement of a series of furnaces and ovens; but

What we do claim and desire to secure by Letters Patent is—

The arrangement of the fire chambers A, 10 ovens B and front plate, *d*, in such relation to each other, as to admit the products of combustion to pass through the flues X,

over the top plate of the oven, thence down through the flue F, in front of the fire chamber to the flue G, beneath the oven, 15 substantially in the manner described for the purposes specified.

In testimony whereof we have signed our names before two subscribing witnesses.

JOHN PLANT.
CHAS. G. BALL.
